UNITED STATES PATENT OFFICE.

FRANK RALEY, OF MERIDIAN, MISSISSIPPI.

CAR-DOOR LOCK.

1,027,276.

specification of Letters Patent.

Patented May 21, 1912.

Application filed March 2, 1912. Serial No. 681,075.

To all whom it may concern:

Be it known that I, FRANK RALEY, a citizen of the United States, residing at Meridian, in the county of Lauderdale and State 5 of Mississippi, have invented certain new and useful Improvements in Car-Door Locks, of which the following is a specification, reference being had to the accompanying drawings.

10 This invention relates to new and useful improvements in car door fasteners and more particularly to a fastener adapted for use on sliding doors of box cars, and my object is to provide a device of this character which will securely retain the door in its closed position until such manual operation removes the same.

15 A further object of the invention resides in providing a locking bar which extends diagonally across the door, said locking bar being rotatably mounted thereon and provided with locking hooks at its ends adapted for engagement with keepers or the like on the car proper.

20 Another object of the invention resides in the provision of keepers adapted for engagement with the hooks formed on said locking bar, one of which keepers is secured to the car at an angle to the other.

25 A still further object of the invention resides in providing a device which is extremely simple and durable in construction, inexpensive to manufacture and one which will be very efficient and useful in operation.

30 With these and other objects in view, the invention consists in the novel features of construction, combination and arrangement of parts as will be hereinafter referred to and more particularly pointed out in the 35 specification and claims.

35 In the accompanying drawing forming a part of this application, Figure 1 is a fragmentary side elevation of a car showing my improved door fastener applied to use thereon. Fig. 2 is a horizontal section through the car as seen on line 2-2, Fig. 1. Fig. 3 is a section through the car as seen on line 40 45 3-3, Fig. 1. Fig. 4 is a perspective view of one end of the locking bar; and Fig. 5 is a similar view of the opposite end of the locking bar.

50 In describing my invention, I shall refer to the drawing in which similar reference characters designate corresponding parts throughout the several views and in which 55 1 indicates the side of a car of the usual

box type provided with a door-way 2 adapted to be closed by a sliding door 3. This door 3 is suspended from a guide rod 4 by means of the hangers 5 and is guided at its lower end by means of the guide keepers 6, but while I have described and shown this particular suspension and sliding means for the door, it will be understood that any desired form of sliding door may be provided.

60 Extending diagonally of the door 3 and rotatably mounted in the bearings 7 thereon, is a locking bar 8, said bar being provided with an integral collar 9 thereon, to prevent sliding movement of said bar with respect to the bearings. The lower end of the locking bar is bent at right angles as shown at 65 10 and this angular bent end is then formed into a hook 11 which is adapted to engage an eye or keeper 12 secured to the side of the car 1 adjacent and below one of the guide keepers 6, said keeper or eye 12 having the axis thereof disposed at an acute angle to the horizontal plane of the lower edge of the door. The upper end of said locking bar 8 which projects beyond the side edge of the door 3 is bent to form a hook 70 13, the free end of which is slightly distorted, as shown at 14 and mounted in a cavity 15 in the side rail or bar 16 which limits the movement of said door 3, is an additional eye or keeper 17. This keeper 17 is wholly disposed in a horizontal plane parallel to the planes of the upper and lower edges of said door 3 and the cavity 15 which 75 opens on to the side face of said rail 16 as well as the front face thereof, has the one wall thereof beveled as shown at 18, whereby it will be appreciated that when the door is moved to its closed position, and the bar 8 turned, the hook 13 thereof will 80 85 be disposed in engagement with said keeper 17. In order to manually rotate this bar 8 in its bearings 7, an arm 19 is formed thereon, the free end of which is provided with an opening 20 and a keeper 21 secured to the front face of the door 3 is adapted to receive the free end of said arm therein, when moved in one position, said keeper being also provided with openings adapted 90 95 to align with the opening 20. When this arm 19 is disposed so as to be positioned within the keeper 21, the hooks at the ends of said bar are adapted to engage their respective keepers and in order to lock the same in said position, a locking key 22 is 100 105 provided on the end of a flexible connection

110

23 secured to said door 3, which locking key is adapted to be disposed through the alining openings in said arm 19 and the keeper 21.

5 From the foregoing description of the construction of my device, the operation of the same will obviously be readily understood, but it will be seen that I have provided a simple, inexpensive and efficient device which may be readily operated and which will securely retain the sliding door in effective position on a car.

10 While I have particularly described the elements most well adapted to perform the functions set forth, it is obvious that various changes in form, proportion and in the minor details of construction may be resorted to without departing from the spirit or sacrificing any of the novel features of the invention.

20 Having thus described this invention, what I claim is:—

1. The combination with a car having an opening in one side thereof, and a sliding door therefor; of a rotatable locking bar extending diagonally across the front face of said door, the free ends of said door being bent to form hook portions, eyes secured to said door on opposite sides of the opening therein, the lower eye being dis-

posed in a plane at an acute angle to the horizontal plane of the lower edge of said door, means to rotate said locking bar to dispose the hook portions thereof in engagement with the eyes, and means to retain said locking bar in its effective position.

2. The combination with a car having an opening in one side thereof and a sliding door therein, of a locking bar rotatably mounted on the outer face of said door and extending diagonally thereacross, the end portions of said locking bar being bent to form hooks, one of said hooks having the free end thereof slightly distorted, eyes secured to said car on opposite sides of the door therein, the lower eye being disposed in a plane at an acute angle to the horizontal plane of the lower edge of said door, an arm formed on said locking bar to rotate the latter and cause the hook portions thereof to engage said eyes, and means adapted for engagement with said arm to secure said locking bar in its effective position.

15 In testimony whereof I hereunto affix my signature in the presence of two witnesses.

FRANK RALEY.
